DISPLAY

Lyndon W. Joyce, Greensboro, N. C.

Application July 23, 1936, Serial No. 92,220

7 Claims. (Cl. 223—68)

This invention relates to a combined overall display form and advertising medium. It is essential in such a display that it be compact, simple, inexpensive, light, foldable and demountable. Likewise, it must display the garment so that the seams, reinforced portions and shoulder straps will be exposed to view.

One of the objects of my invention is to provide a full length display for garments, such as overalls, which may be shipped in a knocked-down condition, quickly assembled, and will display the garment to advantage.

Another object is to provide a resilient frame on which the garment may be placed with suitable supports, and at the same time, will carry descriptive advertising matter concerning the garment.

Other objects will be disclosed in the specification and claims forming a part hereof.

20 In the drawing:

Figure 1 is a perspective showing the frame in display position with the garment in dotted lines;

Figure 2 is a perspective of the display in knocked-down position;

Figure 3 is a detail section taken on the line 3—3 of Figure 1;

Figure 4 is a vertical section on the line 4—4 of Figure 3;

Figure 5 is an enlarged detail section taken on the line 5—5 of Figure 1; and

Figure 6 is a vertical section taken on the line 6—6 of Figure 5.

Referring to the drawing, in which similar parts are designated by like numerals:

Numeral 7 designates a display having a lower front piece 8 formed of double U-shaped legs 9 and 10, the inner sides 11 of the legs formed from a single piece of wire and formed below the outer ends 12 and 13. A socket 14 is placed on each end 12 and 13 and spot-welded or otherwise secured thereto, the wire forming the frame continuing beyond the sockets 14 to form cross piece 15, being spot-welded or soldered at 16 to a strut 17 extending from the top 18 of the inner sides 11. The lower portion of the U-shaped legs in the form of feet 19, are V-shaped, coming to a point at 20 and 21.

Pivotedly secured to the cross bar 15 is a U-shaped brace 22, having hangers 23 slidable on the cross bar 15 and spaced from the ends of the cross bar when in collapsed position but in frictional contact with the sockets 14 when in supporting position. A U-shaped spacer member 24 is pivotedly and slidably secured to the lower end

25 of the brace 22, the front face 26 of the spacer member 24 having turned up bends 27 adapted to extend beneath the U-shaped feet 19 and over the points 20 and 21, locking the frame in position. An upper front piece 28, made of a single 5 piece of resilient wire and bent in a substantial U has its free ends 29 and 30 removably supported in the sockets 14. A cross piece 31 is spot-welded or soldered adjacent the top. The sides 32 and 33 of the front piece 28 are bent inwardly at 34 10 to add resiliency and shape to the upper front piece 28. An advertising plate 35 is slid over the top portion 36 of the upper display 28.

As actually used, the top portion 28 is inserted in the socket 14, the legs of the garment being 15 placed on the front piece 8, the legs 9 and 10 of the frame 7 being inserted in the legs of the garment, the garment being raised up over the upper front piece 28, the suspender straps being passed over the cross piece 31 and secured to the buttons 20 on the bib of the overall. The sides of the garment are buttoned around the projection 37 formed in the brace 22. The brace 22 is then moved into position, the bends 27 being snapped over the points 20 and 21, thus locking the display 25 in position.

In shipping, the display will be folded as shown in Figure 2, the front piece 28 being removed from the sockets 14 and the spacer 24 folded up against the lower front piece 8, the whole forming 30 a very compact, light structure.

Numerous variations may doubtless be devised by persons skilled in the art without departing from the principles of my invention. I, therefore, desire no limitations to be imposed on my invention, except such as are indicated in the appended claims.

What I claim is:

1. A display form comprising a lower portion having U-shaped members connected together 40 and adapted to receive a leg of a garment, a support pivotally connected at one end to said form, spacers connected to the other end of said support and having an upturned front locking portion, the lower ends of said U-shaped members 45 being indented to form locking points, the upturned front locking portion being adapted to fit over said points and lock said display in position.

2. A display form comprising a lower portion having U-shaped members connected together 50 and adapted to receive a leg of a garment, an upper portion extending from said lower portion and adapted to display the remainder of the garment, a support pivotally connected at one end to said form, spacers connected to the other end 55

of said support and having an upturned front locking portion, the lower ends of said U-shaped members being indented to form locking points, the upturned front locking portion being adapted 5 to fit over said points and lock said display in position.

3. A display form comprising a lower portion having U-shaped members connected together and adapted to receive the legs of a garment, an 10 upper portion detachably connected to said lower portion to display the remainder of the garment, and means detachably connecting said portions together, a support pivotally connected at one 15 end to said form, spacers connected to the other end of said support and having an upturned front locking portion, the lower ends of said U-shaped members being indented to form locking points, the upturned front locking portion being adapted to fit over said points and lock said display in 20 position.

4. A display form comprising a bifurcated lower frame made from a single piece of resilient material, the bifurcated portion forming legs and having V-shaped feet, the ends of the frame 25 being secured together, a support pivotally and slidably secured to the top of the frame, spacers extending from said support and having upwardly upturned portions, said portions adapted to pass beneath said feet and over the V-shaped portions and lock the support in position.

5. A display form comprising a bifurcated lower frame made from a single piece of resilient material, the bifurcated portion forming legs, the 30

lower ends of said legs being indented to form locking points, the ends of the frame being secured together, a support pivotally and slidably secured to the top of the frame, spacers of resilient material extending from the free end of said support and having outwardly upturned portions, 5 said portions adapted to pass beneath said feet and be sprung over the indents and lock the support in position, sockets formed in the top of said frame, an upper U-shaped frame having its free 10 ends mounted in said sockets.

6. A display form comprising a bifurcated lower frame made from a single piece of resilient material, the bifurcated portion forming legs, the lower ends of said legs being indented to form 15 locking points, the ends of the frame being secured together, a support pivotally secured to the top of the frame, spacers of resilient material extending from the free end of said support and having outwardly upturned portions, 20 said portions adapted to pass beneath said feet and be sprung over the indents and lock the support in position.

7. A display form for overalls or the like comprising a frame divided into an upper and lower 25 portion, a support for said display pivotally connected to the upper end of the lower portion, the lower portion having locking projections, resilient means on said support adapted to be sprung over said projections for locking said support in 30 supporting position.
